UNITED STATES PATENT OFFICE

DELBERT J. SLACK, OF LOS ANGELES, CALIFORNIA

DESIGN FOR A COMBINATION CIGARETTE HOLDER AND ASH TRAY

Application filed September 3, 1931. Serial No. 41,014. Term of patent 7 years.

To all whom it may concern:

Be it known that I, DELBERT J. SLACK, a citizen of the United States, residing at Los Angeles, in the county of Los Angeles and State of California, have invented a new, original, and ornamental Design for a Combination Cigarette Holder and Ash Tray, of which the following is a specification, reference being had to the accompanying drawings, forming part thereof.

I claim:

The ornamental design for a combination cigarette holder and ash tray as shown.

DELBERT J. SLACK.
